WILLIAM T. HORMES, OF GOVANSTOWN, MARYLAND, ASSIGNOR TO SOLOMON HIMMEL,
OF BALTIMORE, MARYLAND.

DISPLAY-RACK.

1,133,861.

Specification of Letters Patent. Patented Mar. 30, 1915.

Application filed November 9, 1914. Serial No. 871,049.

To all whom it may concern:

Be it known that I, WILLIAM T. HORMES, a citizen of the United States, residing at Govanstown, in the county of Baltimore and State of Maryland, have invented new and useful Improvements in Display-Racks, of which the following is a specification.

This invention is a device for displaying or exhibiting goods, and relates to that type of display device wherein a rotatable rack is employed for supporting the goods to be displayed, which rack is movable to and from a position within a case or compartment. Such cases or compartments are usually constructed with glass walls or panels, so that the goods on display may be readily seen by prospective customers passing the same, and at the same time be protected from dust and contamination from other sources. When it is desired to more closely inspect the goods upon display, the rack is moved to the forward edge of a case or compartment, and then rotated at will, to permit of convenient inspection and selection. In view of the fact that economy of floor space demands that the area occupied by the case or compartment be as small as possible, said case or compartment is usually made of oblong shape, and the arms of the rack, when the latter is within the case, normally extend parallel with the rear wall of the case, the length of said arms being greater than the width of the case. To provide the necessary clearance for the arms of the rack when the latter is rotated, it is customary to provide means whereby the rack may be bodily moved to a point near the front of the case. Under these conditions it is important that the arms of the rack be brought parallel with the rear wall of the case, before the rack is moved back after the goods has been inspected. Otherwise the glass panel forming the rear wall may be damaged or broken by the ends of said arms striking against it.

One of the objects of this invention is to provide a display rack of the character referred to, with means for automatically causing the arms of the rack to assume a predetermined position parallel with the back of the cabinet, after said rack has been rotated in displaying the goods to a prospective customer.

A further object is to provide means for restraining rotation of the rack while the same is in its rear position within the case,

and during its bodily movement to and from said rear position.

The invention will be hereinafter fully set forth and particularly pointed out in the claims.

In the accompanying drawings:—Figure 1 is a plan view illustrating a case containing my improved display rack, the top of the case being removed, the rack being within the case. Fig. 2 is a similar view illustrating the rack in its outer position. Fig. 3 is a longitudinal sectional view illustrating details of construction of the rack, parts being broken away. Fig. 4 is an enlarged plan view illustrating the guide. Fig. 5 is a bottom plan view of the carriage. Fig. 6 is a detail view of one of the pins coöperating with the guide.

Referring to the drawing, 10 designates the case of any suitable or preferred construction, that shown being provided with front sections 11, preferably constructed of glass, and capable of being removed to permit movement of the display rack to a forward position. The bottom of the case is provided with a channel 13, the upper edges of which are formed as guides 14, between which the carriage 15 is mounted to reciprocate. Said carriage is provided with a tubular boss 16 which rotatably supports a shaft 17.

The under face of the carriage is provided with a cam flange 18 provided with the cam faces 19, the neutral faces 20,—and the locating recesses 21. The lower end of the shaft 17 projects below the carriage, and centrally with respect to the flange 18, and is provided with a cross head 22. Said cross head is provided with tubular arms having upper and lower slots 23 through which project the shanks of pins 24, said pins being provided with upper and lower enlarged heads 25 and 26 respectively. Springs 27 within the arms of the cross head engage the pins and act to hold the latter at the outer extremities of the slots. The upper heads 25 are normally in engagement with the interior of the cam flange 18.

Secured to the bottom of the channel in any suitable manner is a guide member 28 extending longitudinally of said channel and transversely of the case. Said guide member is provided with longitudinal grooves 29 which enter an enlargement 30 at the front end of the guide member, the

walls of said opening being shaped to conform the contour of the cam flange 18. It is obvious, however, that the forward or front wall of this opening may be omitted. The lower heads 26 carried by the cross head engage the grooves 29 or the opening 30, according to the position of the rack.

To the upper end of the shaft 17 is secured a cross head 31 to which are secured the arms 32 which support the garment carrying rods 33.

In practice, the heads 25 normally engage the locating recesses 21, when the rack is in its rearward position, and the heads 26 engage the grooves 29. This engagement of the pins 24 with the grooves 29 prevents rotation of the shaft 17, and the parts carried by it, when the rack is in its rearward position. Rotation is likewise prevented during the forward movement of the rack and until the heads 26 of the pins 24 enter the enlargement 30 of the guide member. The enlargement 30 and the cam flange 18 are of such size as to permit rotation of the shaft. As the shaft is rotated however, the heads 25 engage the cam faces 19, compressing the springs 27. Should the force acting to rotate the rack be relaxed, the springs 27 acting against the pins 24 and through the latter against the cam faces 19, will cause the rack to return to its predetermined position with the pins in engagement with the locating recesses 21, and the rods 33 parallel with the back of the case. If, however, the rotating power is continuously applied, the pins will be caused to engage the neutral faces 20, whereupon if the rack is released it will remain in position with the rods 33 extending transversely of the case. When in this position, the rack cannot be moved backward because the rear wall of the enlargement 30 acts as an abutment, and the springs 27 have been compressed practically to their limit, thereby preventing further inward movement of the pins. A rotation of the shaft in either direction will then bring the pins into engagement with the cam faces 19, whereupon the rack will be automatically righted to its predetermined position, and the pins 24 then being opposite the grooves 29, the carriage may be moved to its rearward position.

Having thus explained the nature of my invention, and described an operative manner of constructing and using the same, although without attempting to set forth all of the forms in which it may be made, or all of the forms of its use, what I claim is:—

1. In a display rack of the character described, the combination with a case or cabinet, of a rotatable rack mounted to reciprocate to and from a position within the case or cabinet, a cam member independent of the rack and movable with the latter in its reciprocable movement, and spring pressed

members carried by the rack and in engagement with the cam member to automatically cause the rack to assume a predetermined position with respect to said case or cabinet.

2. In a display rack of the character described, the combination with a case or cabinet, of a carriage mounted to reciprocate within said case or cabinet, a cam flange rigidly secured to said carriage, a rotatable rack supported by said carriage, and spring pressed members carried by the rack and in engagement with the cam flange to automatically cause the rack to assume a predetermined position with respect to said case or cabinet.

3. In a display rack of the character described, the combination with a case or cabinet, of a carriage mounted to reciprocate within said case or cabinet, a cam flange rigidly secured to the underside of said carriage, a rotatable rack supported by the carriage, a cross head secured to said rack, and spring pressed members carried by said cross head and engaging said flange.

4. In a display rack of the character described, the combination with a case or cabinet, of a rotatable rack mounted to reciprocate to and from a position within the case or cabinet, a cam member independent of the rack and movable with the latter in its reciprocable movement, a cross head secured to the rack and having slotted arms, pins projecting through the slots of said arms, and springs holding said pins into engagement with said cam member.

5. In a display rack of the character described, the combination with a case or cabinet, of a rotatable rack mounted to reciprocate to and from a position within the case or cabinet, a cam member independent of the rack and movable with the latter in its reciprocable movement, said cam member having cam faces and locating recesses, and spring pressed members carried by the rack and in engagement with the cam member.

6. In a display rack of the character described, the combination with a case or cabinet, of a rotatable rack mounted to reciprocate to and from a position within the case or cabinet, a cam member independent of the rack and movable with the latter in its reciprocable movement, said cam member having cam faces, neutral faces, and locating recesses, and spring pressed members carried by the rack and in engagement with the cam member.

7. In a display rack of the character described, the combination with a case or cabinet, of a rotatable rack mounted to reciprocate to and from a position within the case or cabinet, a cam member independent of the rack and movable with the latter in its reciprocable movement, spring pressed members carried by the rack and in engagement with the cam member to automatically cause

the rack to assume a predetermined position with respect to the case or cabinet, and means for preventing rotation of the rack when in its rearward position within the 5 case or cabinet and during its movement to and from said rearward position.

8. In a display rack of the character described, the combination with a case or cabinet, of a rotatable rack mounted to reciprocate to and from a position within the case or cabinet, a cam member independent of the rack and movable with the latter in its reciprocable movement, spring pressed members carried by the rack and in engagement with 15 the cam member to automatically cause the rack to assume a predetermined position with respect to the case or cabinet, and a guide member secured to the case or cabinet and having means to engage said spring 20 pressed members to prevent rotation of the rack.

9. In a display rack of the character described, the combination with a case or cabinet, of a rotatable rack mounted to reciprocate to and from a position within the case or cabinet, a cam member independent of the rack and movable with the latter in its reciprocable movement, spring pressed members carried by the rack and in engagement 25 with the cam member to automatically cause the rack to assume a predetermined position with respect to said case or cabinet, and a guide member secured to the case or cabinet and provided with longitudinal 30 grooves to engage said spring pressed members, and an open space at its front end communicating with said grooves.

10. In a display rack of the character described, the combination with a case or cabinet, 40 of a carriage mounted to reciprocate within said case or cabinet, a cam flange rigidly secured to said carriage, a rotatable rack supported by said carriage, a guide member secured to said case or cabinet, and 45 spring pressed pins carried by said rack and engaging said cam flange and said guide member.

11. In a display rack of the character described, the combination with a case or cabinet, 50 of a carriage mounted to reciprocate therein, a cam flange rigidly secured to the

underside of said carriage, a rotatable rack supported by the carriage, a cross-head secured to the rack and rotatable within said flange, a guide member secured to the case 55 or cabinet below said carriage, and spring pressed pins carried by said cross head and engaging said flange and said guide member.

12. In a display rack of the character described, 60 the combination with a case or cabinet, of a carriage mounted to reciprocate therein, a cam flange rigidly secured to the underside of said carriage, a rotatable rack supported by said carriage, a cross head secured to the rack and having slotted arms, 65 said cross head being rotatable within said flange, a guide member provided with grooves and an open space at one end communicating with said grooves, pins projecting through the slots of the arms of said cross head and engaging said flange and the grooves or open space, respectively, of said guide member, and springs acting to press 70 said pins outwardly. 75

13. In a display rack of the character described, the combination with a case or cabinet, of a rotatable rack mounted to reciprocate to and from a position within the case or cabinet, and a cam member movable 80 with the rack in its reciprocable movement, said cam member having cam faces, neutral faces and locating recesses, and a spring pressed device in engagement with the cam member. 85

14. In a display rack of the character described, the combination with a case or cabinet, of a rotatable rack mounted to reciprocate to and from a position within the case or cabinet, and a cam member movable 90 with the rack in its reciprocable movement, said cam member being provided with portions for neutralizing the automatic movement of the rack at predetermined stages in the rotation of the latter. 95

In testimony whereof I have hereunto set my hand in presence of two subscribing witnesses.
